UNITED STATES PATENT OFFICE.

GERTRUDE OLSEN, OF DAWSON, MINNESOTA.

UNDERGARMENT.

1,181,341.

Specification of Letters Patent.

Patented May 2, 1916.

Application filed July 23, 1915. Serial No. 41,540.

To all whom it may concern:

Be it known that I, GERTRUDE OLSEN, a citizen of the United States, residing at Dawson, in the county of Lac qui Parle and 5 State of Minnesota, have invented certain new and useful Improvements in Undergarments, of which the following is a specification.

This invention relates to an improved 10 undergarment of the type worn by small children and the principal object of the invention is to provide a garment so constructed that it may be easily put in place and may be very easily laundered.

15 Another object of the invention is to so construct the garment that it may be formed from two pieces of material thus permitting it to be very easily and cheaply made.

Another object of the invention is to so 20 construct this garment that when in use it will remain securely closed and will remain in the proper position without the need of a drawing string or auxiliary supporting means.

25 This invention is illustrated in the accompanying drawings, wherein:—

Figure 1 is a perspective view of the improved garment looking from the rear side. Fig. 2 is a perspective view of the improved 30 garment looking from the front side. Fig. 3 is a view of the blank forming the rear and side portions of the garment. Fig. 4 is a view of the blank from which the front portion of the garment is formed.

35 The rear and side portions of this garment are formed from the blank 10 shown in Fig. 3, the lower portion 11 of which forms the legs and the upper portion of which forms the body portion. A tongue 40 12 which forms the rear flap is cut from the blank and is provided with a binding 13 having button holes 14 formed therein so that the flaps may be held in the closed position by means of buttons 15. The side 45 portions 16 are extended as clearly shown in this figure and cut diagonally so that when the garment is completely made as shown in Figs. 1 and 2 it will have the proper shape with the side portions 16 overlapped by the front section 17. This front 50

section 17 is formed from the blank shown in Fig. 4 and is provided with button holes 18 so that the front portion may be releasably connected with the side portions of the rear section by means of the buttons 19. 55 This front section is provided with extensions 20 completing the legs of the garment and has its lower portion provided with a cutout 21 similar to the cutout 22 of the blank shown in Fig. 3 so that the two sections may be sewed together at the edges of the cutouts 21 and 22 thus forming a complete garment. It will thus be seen that when forming this garment it is simply necessary to sew the sections together at the 60 edges of the cutouts 21 and 22 and the garment will be ready for use. 65

When this garment is to be used the rear flap will be held in the raised position by means of buttons 15 and after being put in 70 place can be secured by means of buttons 19. It will thus be seen that this garment can very easily be placed upon the child since it is not necessary to pass the child's legs through the leg extensions but it is simply 75 to place the child flat upon the garment and then button the front section to the side portions of the rear section. It will be also noted that this garment can be very easily removed and further that it can be very 80 easily laundered and ironed. It should be further noted that the child's stomach will be protected from cold and thus danger of catching cold eliminated.

What is claimed is:—

85 An undergarment including a rear section having a tongue cut from within its upper end portion to form a closure flap and waist band strap, the strap being severed intermediate its length and having its end portions secured in overlapping relation, a forward section connected with said rear section, and means for releasably holding the closure flap in a closed position.

90 In testimony whereof I affix my signature 95 in presence of two witnesses.

GERTRUDE OLSEN.
